UNITED STATES PATENT OFFICE.

MAURICE LACHMAN, OF NEW YORK, N. Y.

GRATING.

Application filed January 9, 1925. Serial No. 1,369.

To all whom it may concern:

Be it known that I, MAURICE LACHMAN, a citizen of the United States, and a resident of New York, in the county of New York and State of New York, have invented certain new and useful Improvements in Gratings, of which the following is a specification.

My invention relates to metal gratings of the kind especially adaptable for use as side-walk or floor gratings and useful for other purposes as well and the object of the invention, among other things, is to provide a grating that shall be of great strength and stiffness and free from liability to twisting or tilting of the members of the grating upon one another and that shall at the same time not afford ready opportunity for the collection of dirt and shall likewise afford a maximum of light opening for the amount of material entering into the construction.

A further object of the invention is to provide a grating that may be cheaply constructed entirely from standard rolled bars.

The invention will be described in connection with the accompanying drawing, from which description the novel features of construction and the manner in which the objects and purposes of my invention are accomplished will be manifest, and then pointed out in the claims.

Fig. 1 is a plan of a portion of a grating embodying my invention.

Fig. 2 is a cross-section on the line 2—2 of Fig. 1.

Fig. 3 shows a length of rolled metal bar suitable for being transversely sectioned into divisions or portions that may be employed as spacing members in my invention.

Fig. 4 is a cross-section through Fig. 3 on the line 4—4.

Fig. 5 shows a preferred form of spacing member especially useful as the spacing member or insert of my invention.

Fig. 6 shows the manner of use of the spacing member shown in Fig. 5 by illustrating in plan a fragment of the grating and makes clear also the position of the welds as indicated at 3 in the case of one of them.

Fig. 7 shows in section a modified form of channeled spacing insert that may be em-

ployed in carrying out the invention in place of the special form shown in Fig. 1.

Referring to the accompanying drawings: 1 indicates the parallel spaced principal members of the grating spaced apart by spacing inserts or members 2. Said spacing inserts consist each of a flanged member of any of the forms shown in end view or section in the various figures or of any other form providing a web or body portion the edges of which are flanged, the outer face of each flange being at substantially right angles to the plane of the web. These forms permit the utilization of a section or portions of a rolled metal bar cut up into suitable lengths by transversely sectioning the bar to provide the aforesaid inserts or spacing members. Said bar may be of the form for instance shown in cross section in Figs. 4 and 4, said spacing sections being obtained by transversely cutting the rolled metal bar into suitable lengths as indicated by the cross dotted lines in Fig. 3. If desired, however, the special form of flanged spacing member shown in Fig. 7 might be employed in place of that indicated in Fig. 1 or, and preferably, each member might be of the form indicated in Fig. 5 and consist of a section of rolled flanged or channel bar of I form or double channel form affording flanges useful like those of the single channel bar or member but with the advantage to be presently described over the single channel bar or member.

As clearly shown in the figures, the outer faces of the flanges of each spacing member or insert which before sectioning are the flanges of the flanged bars engage against the flat faces of the parallel members 1 while the web part of each member or section of the bar extends across the space between the said members and at right angles thereto and the plane of each web part is practically transverse to the general plane of the grating. Each said insert is fastened securely to the bars 1 by its opposite flanges preferably by electric welds one of which is indicated in dotted lines at 3.

In welding these parts together I employ preferably the resistance process of welding, and the welding electrode is applied to the outer face of the bar or bars, the welding pressure being exerted in line with the web

part 1' of the spacing member which extends across the space between the bars 1. As will be seen, by thus disposing the flanged spacing inserts, the web part 1' affords a support which effectually sustains the welding pressure and permits a good weld to be made.

In constructing the grating from the parts suitably assembled the work may be done one section at a time or it is even possible to weld two or more sections at once owing to the rigid manner in which the parts are sustained in their finished relation by the manner of disposing the flanged inserts. Furthermore it will be seen that the flat outer faces of the flanges afford extended bearing surfaces against the flat surfaces of the parallel members and thus effectually resist the tendency to twisting or distortion of the finished grating. Furthermore it will be seen that the grating affords a minimum obstruction to the passage of light and that there are no pockets which can readily collect dirt or refuse. This freedom from tendency to collect dirt is accentuated by the use of the particular form of insert illustrated in Fig. 1 in which the flange tapers outwardly from the web part, thus affording a wide angle at the meeting point of the inner side of the web part and the inside of the flange or side of the channel.

I do not limit myself to this form of channel section as the form illustrated in Fig. 7 might be used but with less advantage so far as relates to freedom from collection of refuse.

Furthermore it will be seen that the particular form shown in Fig. 1 has advantages in respect to strength at the point where the welding pressure is employed since it is desirable that the weld be made near the position of the web 1'.

In the form of my invention illustrated in Fig. 1, when the weld is made near the base of the channel, as shown, there may be some undesirable tendency to the formation of the flash or bur of heated metal which might be forced out sidewise beyond the line of the underside of the channel, thus forming an unsightly projection in the corner which would moreover tend to collect dirt. The double channel or I-form of spacing member which is illustrated in Fig. 5 and which may each be a section of rolled metal bar ordinarily described as an I-bar may be used to obviate the latter objection. In using this form the insert section or member is employed in the same way as the channel section illustrated in Fig. 1. In this case the head and foot of the I-section constituting the flanges extend in opposite directions from the stem or web part so that when the weld is formed in line with said stem there can be no possibility of the flash or bur of the weld being extruded or exposed while at the same

time the web is in position to effectually sustain the pressure of the tool used in fastening the insert members in position.

By the use of my invention it will be seen that a grating may be readily constructed from ordinary rolled metal bars or shapes as they come from the mill by cutting up the flanged bars into sections or lengths of bar suitable to form the desired depth vertically or transversely of the general plane of the grating and that said shapes particularly lend themselves to the assembling and electric welding of the elements of the grating together in a manner to form a grating of great strength and great resistance to twisting or tilting owing to the wide bearings afforded by the flanges and to the fact that the flat outer faces of the flanges and the flat faces of the bars are effectually secured together by the cheap process of resistance welding.

Furthermore the grating may be made of very pleasing appearance and will be free from the objection of readily collecting dirt. It will also give a greater light area than many previous forms of grating and is well adapted to sustain heavy loads when used as a floor or pavement grating. It also affords a large wearing surface and is far superior to those forms in which strength is aimed at by employing crossing members notched into parallel bars or members.

What I claim as my invention is:—

1. A grating comprising principal parallel spaced members consisting of a series of bars set on edge and independent flanged spacing members, the flange of each said flanged members lying flat against the inside flat of the bar while the web of the flanged member extends at right angles from the bar engaged by said flange and across the space between bars, and with the plane of each web disposed transversely to the general plane of the grating.

2. A grating comprising parallel spaced members consisting of bars presenting to the space between them flat surfaces and spacing inserts consisting of disconnected channeled members the flanges of which engage at their outside flat surfaces against the opposed surfaces of said series of bars and are welded thereto to comprise the spacing members of the structure, the plane of the web of said channel being disposed at right angles both to the general plane of the grating and to the planes of said parallel bars.

3. A grating comprising a series of parallel spaced members having opposed flat faces and spacing inserts consisting of elements I-shaped in cross-section and having the head and foot of each I-section engaged at its outside with the flat opposed surfaces of the parallel bars and welded thereto on a plane including the web of the ele-

ment, the web of each I-section being disposed in a plane transverse to the general plane of the grating and describing approximately a right angle to the opposed faces of the parallel members.

4. A grating comprising parallel spaced members consisting of a series of bars set on edge and spacing inserts consisting of flanged members the flanges of which taper outwardly from the web portion of the member, said flanges engaging by their flat outer surfaces and being welded to the opposed faces of the parallel bars while the web part of the member is disposed transversely to the general plane of the grating and the web itself extending substantially at right angles from the faces of said parallel members.

5. As a new article of manufacture, a metal grating comprising parallel spaced members and interposed spacing inserts consisting of transverse sections of rolled flanged metal bars with the web of each section transverse to the plane of the grating and each said section engaging by the flat outer face of each flange against the flat face of said members and being welded thereto as and for the purpose described.

6. As a new article of manufacture, a metal grating comprising parallel spaced members and spacing inserts electrically welded between said members and consisting of divisions of transversely sectioned rolled flanged metal bars disposed with the web of each section transverse to the plane of the grating and to the plane of the parallel members and engaging by the flat outer face of the flange against one face of the members, the weld between the insert and member being on a line with the web portion of said insert.

7. A grating comprising longitudinally extending spaced supporting members and spacing inserts secured between said members, said inserts comprising separate transverse sections of flanged bars disposed transversely of the plane of the grating, the outer faces of said inserts being welded to said members, the webs thereof serving to space said members and to receive the pressure applied to said members during the welding process.

Signed at New York in the county of New York and State of New York this 8th day of January A. D. 1925.

MAURICE LACHMAN.
